CLAIM

The ornamental design for a goblet or similar article, substantially As shown and described.

DESCRIPTION

FIG. 1 is a front elevational view of a goblet or similar article showing my new design;

FIG. 2 is a rear elevational view thereof;

FIG. 3 is a top plan view thereof;

FIG. 4 is a bottom plan view thereof;

FIG. 5 is a sectional view thereof, taken along the lines 5—5, as shown in FIG. 3, looking in the direction of the arrows;

FIG. 6 is a sectional view thereof, taken along the lines 6—6, as shown in FIG. 1, looking in the direction of the arrows;

FIG. 7 is a sectional view thereof, taken along the lines 7—7, as shown in FIG. 1, looking in the direction of the arrows; and

FIG. 8 is a sectional view thereof taken along the lines 8—8 of FIG. 1, looking in the direction of the arrows, and also of the parfait glass of FIG. 9, taken along the lines 8—8 of FIG. 9, looking in the direction of the arrows;

FIG. 9 is a front elevational view of a goblet in the nature of a parfait glass showing my new design;

FIG. 10 is a sectional view thereof, taken along the lines 10—10 of FIG. 11, looking in the direction of the arrows;

FIG. 11 is a top plan view thereof;

FIG. 12 is a bottom plan view thereof;

FIG. 13 is a sectional view thereof, taken along the lines 13—13 of FIG. 9, looking in the direction of the arrows; and

FIG. 14 is a sectional view thereof, taken along the lines 14—14 of FIG. 9, looking in the direction of the arrows.
